(57) CLAIM

(21) Appl. No.: **29/162,766**

The ornamental design for an elastic member of an elastic coupler, as shown and described.

(22) Filed: **Jun. 20, 2002**

DESCRIPTION

(30) Foreign Application Priority Data

Dec. 21, 2001 (KR) 2001-35922

FIG. 1 is a front perspective view of an elastic member showing our new design;

(51) LOC (7) Cl. **08-08**

FIG. 2 is a back perspective view thereof;

(52) U.S. Cl. **D8/382**

FIG. 3 is a front view thereof;

(58) Field of Search D8/382, 383; 403/403,
403/322.4, 322.1, 217; 464/73, 88

FIG. 4 is a back view thereof;

(56) References Cited

FIG. 5 is a left side view thereof;

U.S. PATENT DOCUMENTS

FIG. 6 is a right side view thereof;

2,034,001 A * 3/1936 Ricefield 464/73

FIG. 7 is a top plan view thereof;

2,588,158 A * 3/1952 Peirce 464/73

FIG. 8 is a bottom plan view thereof;

D227,528 S * 7/1973 Wahl D8/382

FIG. 9 is a cross-sectional view thereof taken along lines

4,094,417 A * 6/1978 Cairnes et al. 211/183

9—9 in FIG. 5; and,

FIG. 10 is a cross-sectional view thereof taken along the

lines 10—10—10 in FIG. 3.
